(57) **CLAIM**

The ornamental design for a lamp holder for screen lamp as shown and described.

DESCRIPTION

FIG. 1 is a front, right, bottom perspective view of a lamp holder for screen lamp, showing our new design;

FIG. 2 is a rear, right, top perspective view thereof;

FIG. 3 is a front view thereof;

FIG. 4 is a rear view thereof;

FIG. 5 is a left side view thereof, a right side view being a mirror image;

FIG. 6 is a top view thereof; and,

FIG. 7 is a bottom view thereof.

The straight broken lines illustrate feature lines of the article that form no part of the claimed design. The broken line circles and the surface within illustrate portions of the article that form no part of the claimed design.

1 Claim, 5 Drawing Sheets
